UNITED STATES PATENT OFFICE

HENRY LANGE, OF QUINCY, ILLINOIS, ASSIGNOR TO QUINCY STOVE MANUFACTURING CO., OF QUINCY, ILLINOIS

DESIGN FOR A CABINET TYPE GAS RANGE

Application filed January 23, 1933. Serial No. 46,944. Term of patent 14 years.

To all whom it may concern:

Be it known that I, HENRY LANGE, a citizen of the United States, and a resident of the city of Quincy, county of Adams, and State of Illinois, have invented a new, original, and ornamental Design for Cabinet Type Gas Ranges, of which the following is the specification, and reference being had to the accompanying drawing, forming a part thereof.

The figure is a perspective of the gas range of my invention illustrating the essential fea-

tures of its design. This range has the top slightly elevated over the oven which is centrally disposed and has the control panel approximately flush with the front face of the oven and with the border of the control panel extending forward flush with the flange about the top.

I claim:

The ornamental design for a cabinet type gas range as shown and described.

HENRY LANGE.
